UNITED STATES PATENT OFFICE.

FRANK J. PFIFFNER, OF JOLIET, ILLINOIS, ASSIGNOR OF ONE-HALF TO JAY W. ELLIOTT, OF MINNEAPOLIS, MINNESOTA.

ERECTING MACHINE FOR WALL BOARDS.

Application filed December 31, 1925. Serial No. 78,634.

My invention relates to improvements in erecting machines for wall-boards, and the object of my improvement is to furnish a device effective for adjustably supporting the sheathing of this character, such as plaster-boards for ceilings, so that the plates thereof may be easily and accurately fitted in place and may be then secured rapidly to the supporting timbers therefor.

10 This object I have accomplished by the means which are hereinafter described and claimed, and illustrated in the accompanying drawings, it being understood that changes in the precise embodiment of invention herein disclosed can be made within the scope of what is claimed without departing from the spirit of the invention.

In said drawings, Fig. 1 is a front elevation of my device, with parts broken away, 20 the dotted lines indicating the projected position of the adjustable table. Fig. 2 is an end elevation of said device, and Fig. 3 is a plan thereof.

25 Wall boards, particularly those constructed of plaster, are both bulky and heavy, being inconvenient to mount and fasten upon a wall or ceiling beams. With my device, both operations may be effected quickly and easily by a single workman, with a consequent economy of labor and time.

30 The device comprises a transportable supporting structure, and an adjustable table for the wall-board slidably reciprocable therein, with means for lifting or lowering the table, and means for adjustably inclining the table.

The supporting structure comprises two spaced pairs of standards 1 mounted fixedly between base-blocks 2 on plates 4 and secured 40 by bolts 3. Boards 6 are mounted upon the base-blocks to front and rear of the standards 1. The interspaces of the base-blocks and of the pairs of standards 1 afford slide-ways for vertically reciprocable table slides 32 and leg-members 12 connected to the slides by means of bolts 11 without the standards 1. The members 12 support a 45 tiltably adjustable table-top made up of rigidly jointed longitudinal parallel transversely spaced bars 14 and divided sectional cross-bars 15, one set of the latter having a single upwardly extending rail or bar 16 secured upon the outer front ends thereof as a wall-board abutment.

Arcuate plates 17 are overlapped and have 55 end flanges 18 secured by bolts 19 depending from opposite end parts of the longitudinal bars 14, the plates 17 having a plurality of holes 41 therearound each hole 41 in one plate adapted to register in turn with any 60 hole in the other plate of the pair, and with a bolt-hole in each case in the upper part of the standard 12, and whereby a fastening bolt and compression nut 20 and 21 may be 65 used to hold and fasten the table halves horizontal or in any adjusted tilted position, or with the halves of the table collapsed for any purpose, so that a plate of wall-board 42 upon the table-top and abutting the abutment rail 16 may be apposed to ceiling rafters whether the latter are horizontal or in any way slopingly arranged. Cross-blocks 70 33 are arranged to abut opposite faces of each set of slides 32 and standards 1 and secured by bolts 34 to the slides, to hold the 75 slides in vertical positions in the slideways between the standards.

The transversely spaced standards 1 are 80 rigidly connected at their tops at both front and rear by longitudinal beams 7, cross-beams 8 being connected between the beams 7 abutting upon the inner faces of the standards 1, the beams 7 being secured by bolts 13. On the inner medial faces of the cross-beams 8 are fixed staples in which are 85 hung the eyes of pulley-blocks 22 and 23 respectively over whose sheaves are reeved short cables 24 and 25, their inner ends being secured to opposite parts of a winding-drum 26 to wind thereon. The other ends 90 of said cables are secured to the inner ends of headed bolts 11 near the lower ends of the slides 32.

Longitudinal bars 9 connect the standards 1 on their front and rear faces and are secured thereto by bolts 10 and have thereon medial bearings 29 which seat a rotatable shaft 27 on which said winding-drum is secured between said bars. On the same shaft 95 is also fixed a ratchet-wheel 30 whose teeth are engaged by a pawl 31 of the gravity type 100 rockingly mounted on a rigid standard 29' rising from the upper member of the bearing-box 29. The shaft 27 has an end crank 28 provided with a handle.

Referring to said Fig. 2, the numeral 35 denotes a pair of spaced arms whose like ends nearest the standards 1 are pivoted

thereto to swing up and down at 39. The outer ends of these arms are rigidly connected by means of a plank 36 thereon which serves as an elevated footing for the 5 machine operator, while placing and fastening overhead wall-boards. The plank has near each end depending blocks 37 to which a pair of legs 40 are pivotally connected at 38. It will be seen that this footing is collapsible, by swinging the legs 40 past each other, and then the arms 35 may be swung downwardly to lie vertically against their inner faces in front of standards 1 on which they are pivoted.

15 A sheet of wall-board 42 having been placed upon the table-top and having one longitudinal edge abutting upon the rail abutment 16, the crank 28 may be used to rotate the winding-drum 26 to wind up the 20 two cables 24 and 25 to thereby elevate the table to a desired height, the pawl 31 holding the table at the desired height in thus keeping the plate 42 in contact with rafters or other supports to which it may be nailed 25 by a workman without other help. The apparatus may be then shifted to another location, when the slides 32 have been lowered.

The tilting of the table-top adjustably permits it to hold a plate 42 against sloping 30 rafters at different inclinations.

The device as a whole is simple, strong and effective.

Having described my invention, what I

claim as new, and desire to secure by Letters Patent, is:

An erecting machine for wall boards, comprising in combination, a basal support, longitudinally spaced pairs of transversely spaced standards fixed upon said support, a slide-beam slidably mounted between each 40 pair of standards, a connecting device between the upper ends of the standards, pulleys supported on the end parts of said connecting device, spaced bars connecting the middle parts of said standards, a winding 45 drum rotatably mounted on and between said bars, a ratchet-wheel mounted on one end of said drum, a pawl rockably mounted upon one of said bars to movably engage 50 teeth of said ratchet-wheel under the influence of gravity, cables attached to said winding drum and directed oppositely therefrom around said pulleys and terminally fastened to the lower parts of said slide-beams, oppositely projecting arms adjustably pivoted on the upper parts of said slide-beams, means for holding said arms 55 releasably in different positions, and table-top sections secured in parallel upon said arms to swing up and down, one section 60 having an upwardly directed rib along its outer longitudinal margin to serve as a stop thereon for wall board supported upon the sections.

In testimony whereof I affix my signature.
FRANK J. PFIFFNER.
